CLAIM

The ornamental design for a floating beverage container, as shown and described.

DESCRIPTION

FIG. 1 is a three-dimensional isometric view of a floating beverage container in a first, extended orientation.

FIG. 2 is a three-dimensional isometric view thereof in a second, collapsed orientation.

FIG. 3 is an elevational view thereof, shown in a first, extended orientation.

FIG. 4 is an elevational view thereof, shown in a second, collapsed orientation.

FIG. 5 is a top plan view thereof.

FIG. 6 is a bottom plan view thereof; and,

FIG. 7 is a side sectional view taken about the line of FIG. 3.

1 Claim, 7 Drawing Sheets
